United States Patent Office

Des. 185,330
Patented May 26, 1959

185,330

PLATE OR SIMILAR ARTICLE

Gerald S. Stone, Scarsdale, N.Y., assignor to Johnson Bros. (Hanley) Limited, Hanley, Stone-on-Trent, England, a British company

Application December 29, 1958, Serial No. 53,931

Term of patent 14 years

(Cl. D44—15)

The figure is a top plan view of a plate or similar article of conventional configuration showing my new design.

I claim:

The ornamental design for a plate or similar article, substantially as shown and described.
